W. KOERBER

AUTOMATIC RAILROAD SAFETY GATE

Filed Jan. 24, 1928

UNITED STATES PATENT OFFICE.

WILLIAM KOERBER, OF NEW YORK, N. Y.

AUTOMATIC RAILROAD SAFETY GATE.

Application filed January 24, 1928. Serial No. 249,002.

This invention relates to a new and useful device in the nature of a railroad safety gate especially adapted as a means of guarding railroad crossings.

5 The object of the invention is to provide a railroad safety gate embodying certain new and novel features hereinafter more fully described, claimed and illustrated in the accompanying drawing.

10 Fig. 1 is a top plan view of a railroad crossing showing my improved safety gate installed thereat.

15 Fig. 2 is an enlarged side elevational view of one of my improved safety gates, partly in section so as to more clearly show the construction thereof.

Fig. 3 is a transverse sectional view taken on the line 3—3 of Fig. 2.

20 Fig. 4 is a sectional view of the gate operating mechanism as embodied in my improved device.

Fig. 5 is a top plan thereof.

25 Fig. 6 is a detail view of the gate cylinder, partly in section so as to more clearly show the construction thereof.

Fig. 7 is an end elevational view of the piston as embodied in the gate operating mechanism.

30 Fig. 8 is a transverse sectional view taken on the line 8—8 of Fig. 7.

Fig. 9 is a detail side elevational view illustrating a further development of my improved device.

In Fig. 1 of the accompanying drawing, I 35 have shown the usual railroad tracks 10 and 11, intercepted by the road 12 or highway. The above described constitute an ordinary railroad crossing such as are necessary to allow vehicles, pedestrians and the like to 40 cross the said railroad tracks.

As here embodied my improved device embodies a number of gates each comprising an arm 13 secured intermediately, as at 14, to the vertical rod 15, rotatively mounted in the 45 support 16. The support 16 is provided with a lower flanged element 17, secured as at 18 to the base member 19. The base member 19 is extended across the box 20. The signal lever 21 is hinged at one extremity to the arm 50 13, as at 22, by the usual hinge, and is provided with an enlarged free extremity 23, painted preferably white and having affixed thereto a suitable warning signal 24, painted preferably red or any desired prominent 55 color. The expansion spring 25 is secured

to the lever 21 and to the arm 13, at the said hinge point 22, as a means of normally holding the lever 21 in an extended position.

The rod 15 is rotatively carried in the bearing 26, secured as at 27, to the bottom of the 60 said box 20. The bearing 26 has formed therein an aperture adapted to receive the lower extremity of the said rod 15. The lever 28 is secured intermediately to the lower portion of the rod 15. 65

The gate cylinder 29 is of tubular construction provided with closed ends 30 and 31. The end 30 is provided with a lug element 32 having formed therein an aperture adapted to receive the pin 33, as a means of pivotally attaching the cylinder 29 to the lug element 34, of the bracket 35, secured as at 36, to the end of the said box 20. The piston 37 is slidably mounted in the cylinder 29, and is provided with the usual piston rod 38, ex- 70

tended therefrom through an aperture formed in the said end 31. The extended extremity of the rod 38 is secured as at 39, to the extended extremity of the said lever 28. The cylinder 29 has formed therein, in prox- 75

imity to the end 30 elongated openings 40. The sleeve 41 is slidably mounted on the cylinder 29 and has formed therein an elongated diagonal opening 42, adapted to receive the set screw 43, as a means of securing the sleeve 80

41 to the cylinder 29. The latter described construction is such as will permit the sleeve 41 to be slidably positioned, as designated by the reference numerals 44 and 45, so as to regulate the rate or speed of the return of the 85

piston 37. The tension spring 46 is secured to the opposite extended extremity of the lever 28 and to the side of the box 20, as a means of normally holding the above mentioned lever 21 in the position as hereinafter 90

set forth.

The operating lever 47 is pivotally secured at its lower extremity, as at 48 to the bracket 49, secured as at 50 to the bottom of the box 51 and is normally held in an angularly inclined position by means of the tension spring 77, secured thereto, in proximity to the free extremity of the said lever 47 and to one end of a flexible member 73. 100

The cylinder 52 of tubular construction is provided with closed ends 53 and 54. The end 54 is provided with an extended element 55 having formed therein an aperture adapted to receive the eye bolt 56, as a means of pivotally attaching the cylinder 52 to one end of the 105

110

box 51. The piston 57 is slidably mounted in the cylinder 52 and is provided with the usual piston rod 58 extended through an aperture formed in the end 53. The extended extremity of the rod 58 has formed therein an aperture adapted to receive the eye bolt 59, as a means of pivotally attaching the rod 58 intermediate to the lever 47. Flapper valves 60 are hinged as at 61 to the brackets 62 secured as at 63 to the face of the piston 57 and are adapted to close or cover the apertures 64 formed in the said piston 57. It will be understood that the cylinder 52 is partly filled with glycerine, or the like. The above mentioned box 51 is provided with a top cover 65, having formed therein an aperture, closed or covered by the manhole cover 66, as a means of permitting the gate operating mechanism to be inspected and oiled.

It is understood that a pair of my improved gate operating mechanisms are provided, designated by the reference numerals 67 and 68 positioned intermediate the rails of the said tracks 10 and 11, respectively, at a desired distance from the road 12. It is also understood that four of the above mentioned and described gates are provided, a pair of which designated by the reference numerals 69 and 70 are positioned at the opposite sides of the road 12 any desired distance from the tracks 10 and 11, respectively. The second pair of the above mentioned gates, designated by the reference numerals 71 and 72 are similarly positioned intermediate the gates 69 and 70, respectively.

Referring particularly to Fig. 1, the flexible members 73 are shown secured to the extended extremities of the levers 28 of the gates 69, 70, 71 and 72, and extending over various pulleys for connection with the gate operating mechanisms 67 and 68. These flexible members are shown connected together over the portion of the road where the tracks cross and here extend over various pulleys 80. The arrangement is such that a train approaching the crossing on either one of the tracks moves the lever 47 of one or the other of the mechanisms 67, 68 for drawing upon the flexible members 73. This motion is transmitted to rotate each of the levers 28 for closing all of the gates. It is pointed out that the levers 47 are connected with a dash pot arrangement within the cylinders 52, arranged for very rapidly assuming its extended position. This, very rapidly in turn, turns the gates into danger positions. The dash pot arrangement within the cylinders 52 is arranged for very slowly returning to its original position for very slowly opening the gates from their closed danger positions.

It is obvious that the above described mechanism is such as will permit the warning signals 24 to be pivoted outwardly as designated by the reference numeral 81, when the free extremities of the levers 47 are engaged or

struck by the cowcatcher of a locomotive approaching the road 12, on the tracks 10 or 11, as a means of warning vehicles, pedestrians or the like on the road 12 approaching the tracks 10 and 11, of the said locomotive. It is also obvious that in the event that a vehicle or the like should strike the levers 21, of the above mentioned gates that the said levers will hinge or swing out of the way preventing major injury to either the vehicle or the said levers. It is also obvious that the action of the above mentioned cylinders will allow the said gates to relatively, slowly resume their normal open position, allowing the said train to pass the road 12 prior to the return of the said gates to their normal open position.

In Fig. 9 of the accompanying drawing, I have shown expansion springs 85, co-axial on the rods 87 secured to the flexible member 73 and interposed therein. The rods 87 are slidably mounted in the yoke 89 and are similarly mounted in the adjustable members 90 and 91 respectively, which are slidably mounted in the yoke 89, in proximity to the opposite ends thereof and which are secured hereto by means of the bolts 92 and 93 respectively. The above described construction is such as will permit the said adjustable members 90 and 91 to be positioned relative the extremities of the yoke 89 so as to vary the tensioning of the said flexible member, and which will allow the above described mechanism to function as a shock eliminator as is obvious from the foregoing description. This tensioning means is intended for insertion anywhere along the lengths of the flexible members 73. When these members 73 are suddenly drawn by reason of the locomotive moving the lever 47, these tensioning means will operate for absorbing this sudden shock and then transmit the motion along the flexible members.

Having thus described my invention what I claim as new and desire to secure by Letters Patent of the United States is:—

1. An automatic railroad safety gate, comprising a gate element arranged for moving from normal position to danger indicating position, a dash pot having a piston adapted for moving rapidly from normal position, and slowly back to normal position, a lever connected with the dash pot piston and arranged for engagement by a train to rapidly move the dash pot piston from normal position, springs arranged for urging the dash pot piston back to normal position, the said return motion being very slow, and means for connecting the dash pot piston action with the said gate element for moving the same from normal to danger position as the said piston moves from and to normal positions.

2. An automatic railroad safety gate, comprising a gate element arranged for moving from normal position to danger indicating position, a dash pot having a piston adapted for moving rapidly from normal position, and

slowly back to normal position, a pivoted lever connected with the dash pot piston and arranged for engagement by a train to rapidly move the dash pot piston from normal position, means for urging the dash pot piston back to normal position, the said return motion being very slow, and means for connect-

ing the dash pot piston action with the said gate element for moving the same from normal to danger position as the said piston moves from and to normal positions.

In testimony whereof I have affixed my signature.

WILLIAM KOERBER.
